RIBBON SHIFT MECHANISM

Louis M. Potts, Evanston, Ill., assignor to Teletype Corporation, Chicago, Ill., a corporation of Delaware

Application January 2, 1941, Serial No. 372,718

11 Claims. (Cl. 178—29)

This invention relates to printing telegraph apparatus and more particularly to apparatus for selectively determining the transverse portion of the inking ribbon with which printing is effected.

The principal object of this invention is to provide, in a printing telegraph apparatus, a mechanically simple and inexpensive mechanism for selectively shifting the inking ribbon to interposed relation with the printing element and platen for printing.

Another object of this invention is to provide a ribbon shifting mechanism for an inking ribbon having a plurality of bands of different colors which is selectively operable in response to transmitted and received messages to produce a multi-colored record in which transmitted or received messages may be instantly recognized as such by the color of the message on the record.

A further object of this invention is to provide in a printing apparatus simple and inexpensive mechanism for equalizing wear on the inking ribbon.

In printing telegraph systems, there is generally provided at each substation a transmitter for sending messages and a receiver which may act to produce a home record for transmitted messages and a printed record of received messages. In order to be able to distinguish upon inspection of a printed copy the messages transmitted from those received, this invention features apparatus to produce a printed record in a color which is selectively determined by the transmitter associated therewith.

One printing apparatus with which this particular invention finds utility comprises a type wheel, movable in the course of each printing cycle from a withdrawn position to a printing position. This movement may be imparted to the type wheel through the agency of a cam controlled bail, and the contemplated ribbon shift mechanism comprises a shift frame, movable by such a bail concurrently with the type wheel to interpose a predetermined color band of an inking ribbon, comprising a plurality of color bands, between the type element and the platen for printing. Following the printing step, the type wheel and the ribbon shift frame return to withdrawn position, and thus is provided visible printing. The ribbon shift frame, when recording characters received from a distant substation, is elevated to one height to present one color band to the type element but is permitted by the operation of a slidably stop member controlled by a cam on a shaft in the transmitter to be elevated to a different height to present another color band

to the type element when the printing apparatus acts as a home recorder to record transmitted messages.

In each cycle of the printing apparatus the 5 ribbon shift frame is latched in position to permit the inking ribbon to be elevated to present to the printing point that color band from which received signals are printed. If the next succeeding character to be printed is received from 10 a distant station, the ribbon shift frame is properly conditioned. However, if the next succeeding character originates in the local station the ribbon shift frame must be shifted, and, for this purpose, a cam located on the cam shaft in the local transmitter operates a latch release to shift 15 the ribbon frame.

Depending upon the character of the message material there occurs a preponderance of characters on one level or the other of the type elements and, consequently, one transverse half of the inking ribbon is normally subjected to greater wear than the other half. Another feature of this invention obviates this unequal ribbon wear by providing a ribbon shift frame automatically positioned in each printing cycle to present alternately the upper and lower transverse halves of the inking ribbon to the printing point. For the accomplishment of this result, the ribbon shift frame carries a stop projection extending through 20 a stepped aperture in a cooperating stop member, which is cyclically conditioned by the printing apparatus to alternately place the step in and out of the path of the stop projection, thereby permitting the ribbon frame to travel alternately 25 to two different elevations.

As a still further feature, this invention provides means for manually controlling the travel of the ribbon shift frame to produce equalized wear by providing a manually operated cam to condition the stop member and the ribbon shift frame in either of their two operative positions.

The telegraph apparatus upon which this ribbon shift mechanism has been illustrated is disclosed in Patent No. 2,247,408, granted July 1, 45 1941, to Albert H. Reiber, which is incorporated herein by reference and resort may be had to that application for a more comprehensive description of the structural details and the mode of operation of the printer apparatus which is described herein only generally.

For a more complete understanding of this invention, reference may be had to the following detailed description to be interpreted with the accompanying drawings wherein,

Fig. 1 is a fragmentary front elevational view

of a printing telegraph apparatus embodying one specific application of this invention;

Fig. 2 is a side elevational view, partially broken away, of the apparatus disclosed in Fig. 1;

Fig. 3 is a detailed perspective view of the type wheel shifting frame and ribbon shifting frame of Fig. 1 showing their nested relation to one another;

Fig. 4 is a fragmentary side elevational view of a printing apparatus provided with mechanism for automatically shifting the inking ribbon to equalize wear;

Fig. 5 is a fragmentary plan view of the apparatus disclosed in Fig. 4;

Fig. 6 is a detailed perspective view of the 15 slidable stop member of Fig. 4 and its operating mechanism;

Fig. 7 is a fragmentary side elevational view of a printing apparatus equipped with manual means for shifting the ribbon frame to equalize wear; and

Fig. 8 is a fragmentary plan view of the apparatus of Fig. 7.

Referring now to the drawings and more particularly to Figs. 1, 2, and 3, there is indicated at 11 a casting for supporting a printing apparatus of the type described in the above-identified patent which casting is provided with a vertical supporting column 12 equipped at its upper extremity with a raceway 13 for supporting the roller bearings 14 of a movable carriage structure 16 in which is rotatably supported a platen 17 on a shaft 18. An additional raceway 19 completes the supporting and guiding structure for the movable carriage 16. The carriage structure 16 also supports a paper guiding plate 20 extending beneath the platen 17 which serves to guide paper to the printing point and a plurality of extending fingers 21 integral with plate 20 functioning to maintain the paper in engagement with the platen.

The type wheel 25 is mounted on a shaft 26 and comprises a plurality of radially disposed type elements mounted for reciprocal movement in radial slots provided in the type wheel frame structure. A print hammer 27 is provided to move a selected type element toward the platen 17 to effect printing. Secured to the hub 28 of the type wheel 25 by means of a clamping nut 29, there is provided a radially extending arm 31 having a depending portion 32. An additional radially extending arm 33 is provided and is secured by a clamping bushing 34 to shaft 26. At its distal end, radial arm 33 is bifurcated and the depending portion 32 of arm 31 projects through the bifurcation in a freely slidable manner. Through this mechanism, the driving torque of shaft 26 is transmitted to the type wheel 25 and the sliding engagement of projection 32 with radial arm 33 permits type wheel 25 to be elevated with respect to its driving member 33 while still maintaining driving relation therewith. At 36 there is indicated a portion of the receiving mechanism comprising a plurality of code discs and selecting mechanisms for selectively engaging a stop arm (not shown) in response to a received permutation code signal combination to arrest the type wheel 25 in the desired position to print the character corresponding to the received code signal combination. The structural details, as well as the mode of operation of the selecting mechanism 36, is fully explained in the above-identified patent and, accordingly, will not be set forth herein inasmuch as that portion of the printing appa-

ratus embodies no features of the present invention.

The apparatus disclosed herein provides for visible printing; that is, the type wheel is elevated into the printing position and after the printing has been effected, the wheel is returned to its lower position uncovering the printed character. Accordingly, a lifting bail 42 is rotatably mounted in a supporting structure 41 by means of trunnions 43 and is yieldably articulated to a type wheel shifting frame 46 to elevate that frame and the type wheel in the course of a printing cycle in a manner to be described hereinafter.

Frame member 46 is provided with a vertically disposed slot (not shown) through which a stud 47 carried by the supporting structure of the printing apparatus projects in order to support the frame member 46 in a slidable manner. Frame member 46 is provided with a horizontally extending portion 48 provided centrally with an aperture through which the type wheel shaft 26 projects and in which it is rotatably supported by means of the hub 28 of the type wheel 25. Horizontal portion 48 is perforated at each of its ends to receive guide pins 49 and 51 mounted in a vertical portion 52 of the printing apparatus frame. The guide pins fit freely within the apertured frame member 48 of the type wheel shifting frame 46 so that the latter is freely slidable. A spring 53, see Figs. 2 and 3, extending between bail 42 and a spring post 50 carried by frame 46, provides a yieldable connection between the bail and type wheel shifting frame so that as the bail rotates upon its trunnions under the influence of cams to be hereinafter described, the type wheel will be elevated.

The height to which the type wheel is elevated to determine whether printing is to be effected in upper or lower case characters, is determined by a stop member 54 provided with a stepped aperture 55 and a stop projection 56 carried by frame member 46 and extending through the stepped aperture 55 in member 54 (see Fig. 3). Stop member 54 is provided with horizontally slotted portions 57 and 58 through which studs 59 and 60 carried by the printing apparatus frame project and provide supporting and guiding means for the stop member 54 which accordingly may be shifted horizontally. The position of stop member 54 is determined by the operation of function levers 63 which position stop member 54 through a pair of levers 61 and 62 pivotally supported by stud 47 and engaging respectively at their upper and lower ends the stop member 54 in a manner clearly disclosed in Fig. 5 of the above-identified patent. When the apparatus is conditioned for operating in unshift condition, the shoulder portion 64 of the stepped aperture in stop member 54 is in alignment with the stop projection 56 on frame member 46 and accordingly, when the bail 42 is rotated counterclockwise about its trunnions 43 under the control of the cam shaft of the printing apparatus, the spring 53 will cause the frame 46 to be elevated until stop projection 56 engages the shoulder portion 64 of the stepped aperture 55 and arrests the elevation of the type wheel. In response to the selection of the shift function bar, the stop member 54 is shifted leftwardly, as viewed in Fig. 3, removing the shoulder portion 64 of the stepped aperture from alignment with projection 56 and in this condition when the frame member 46 is elevated, the arrestment of the frame will be delayed until stop projection

56 has passed the shoulder portion of the step and come into engagement with the upper limit of the aperture 55. In other words, when typing from one-half of the type wheel, the carriage is arrested by means of the step of aperture 55 and when operating from the other half, the step is ineffective and the carriage travels until arrested by the stop member 54 at the upper extremity of aperture 55.

The printing apparatus is provided with two cam shafts (see Fig. 2) represented at 66 and 67 with their associated driving gears 68 and 69, respectively, which are caused to rotate for a single revolution in response to the reception by the magnet of the receiver of a code signal combination, whether it be received from a distant station or from the transmitter, to be described hereinafter, associated with the particular printing apparatus. On cam shaft 66 is an elevating cam 71 which operates through a follower 72 to rotate lifting bail 42 counterclockwise about its trunnions 43 to elevate the type wheel shifting frame 46 and, consequently, the type wheel. An internal cam 73 on cam shaft 67 and follower 75 are effective to provide the return of the bail 42 and the type wheel 25 to normal at a controlled speed. Also carried by cam shaft 67 is a cam 74 which is engaged by a cam follower 76, pivoted on member 77 to which member is also pivoted lever 78 which operates the print hammer 27. Accordingly, in response to the reception of a start impulse of a code signal combination, a cycle of operations is initiated in which both cam shafts 66 and 67 are successively released. In the rotation of shaft 66, cam 71 is operative to elevate the bail 42 and to thereby elevate the shift frame 46 and type wheel 25, while internal cam 73 of shaft 67 is effective to maintain a controlled return of bail 42, frame 46, and type wheel 25. At the same time, through the rotation of cam shaft 67 the cam 74 operates its follower 76 and lever 78 to operate the print hammer in timed sequence with respect to the elevation of the type wheel.

A pair of inking ribbon spools 81 are provided which operate alternately as paying-out and take-up reels, only one of which is disclosed in the drawings for the sake of structural clarity of those elements constituting the invention here involved, and the spool is rotatably supported by a stud shaft 82 provided with a driving gear 83. There is indicated at 84 a lever operated in response to the selection of the ribbon feed function bar to feed the ribbon from one spool to another.

The apparatus described up to this point is common with that disclosed in the above-identified patent, and reference may be had to that patent for a more complete understanding of the apparatus herein described above only generally.

The ribbon in passing from one spool to the other is guided around the type wheel 25 by an arcuate guide plate 85, provided with horizontally extending fingers 86 which direct the vertical displacement of the ribbon. The ribbon guide 85 is suspended from a horizontal portion of a ribbon shift frame 87. The ribbon shift frame 87 has a contour very similar to that of the type wheel shift frame 46 and is likewise slidably supported on stud 47 being provided with a vertically disposed slot 88, and being provided in its horizontal portion with two apertures through which guide pins 49 and 51 extend so that this shift frame 87 is mounted

for a sliding movement paralleling that of the type wheel shift frame 46. Also, the articulation between the lifting bail 42 and the ribbon shift frame 87 is through the agency of a spring 90 distended between a projection 89 on the frame member 87 and the bail 42. The ribbon shift frame also carries a stop projection 91 for determining the height to which the ribbon shift frame and consequently the inking ribbon is elevated.

10 The mechanism provided for determining the height to which the ribbon shift frame 87 is elevated comprises a principal slide 92 which is slotted at 93 and 94 and supported by a pair of studs 96 and 47 suitably carried by the frame 15 structure of the printing apparatus. The dimensions of the studs and slots are such that member 92 is freely slidable in a horizontal direction. A spring 98 extending from the frame structure of the printing apparatus to the slide 92 tends to 20 hold the slide in its leftward position, as viewed in Fig. 3. Slide member 92 is provided also with a pair of studs 99, only one of which appears in the drawings, which extend through horizontally disposed slots 101 provided in an auxiliary slide member 102. A spring post or projection 103 is 25 formed at the leftward extremity of slide 102 and a spring 104 is distended between the projection and one of the studs 99, preferably the rightward stud, to provide for a yieldable articulation between the two slide elements to permit a relative 30 sliding of one with respect to the other should the other be maintained against movement at the time it is desired to move one of the slides. This condition which may exist will be explained 35 in detail hereinafter. Slide member 102 which is L-shaped has in its vertical portion a stepped aperture 105 through which the stop projection 91 on the ribbon elevating frame 87 protrudes.

The principal slide 92 is provided with a locking shoulder 107 into which a pivoted locking pawl 108 is adapted to be inserted to normally hold the slide 92 in its rightward position, as illustrated in Fig. 3. Locking pawl 108 is normally spring-urged by a spring 109 into the position 40 shown but is adapted to be rotated about its pivot 111 carried by the printer frame, by the operation of a cam follower 112 and its cam 113 in a manner to be hereinafter described. When 45 pawl 108 is released from engagement with the locking shoulder 107, slide 92 is moved leftwardly under the influence of spring 98 and is subsequently restored by means of a cam 114 carried on cam shaft 66 and engaged by a follower 50 roll 115 on a pivoted lever 117 pivoted at 118 to the printer frame and extending into the path of 55 a projection 119 on the slide 92.

Cam 113 is carried on a transmitting cam shaft of a transmitter associated with the printing apparatus and indicated generally 118 (see Fig. 2). The transmitter employed is the customary start-stop permutation code transmitter, such as that disclosed in the above-identified patent to Albert H. Reiber and since the transmitter is not new, and constitutes no part of this invention, it will not be described herein any more than to indicate it generally and to say that the cam 113 is located as an additional cam upon the conventional transmitting cam shaft which is set into operation cyclically for the transmission of code 60 signal combinations.

The operation of the printing apparatus to provide for a color differentiation between the printed record of messages received and messages transmitted is as follows: Slide member 92

is normally locked by pawl 108 as disclosed in Fig. 2, placing spring 98 under tension and aligning the shoulder portion 106 of the step in aperture 105 with the stop projection 91 on the ribbon shift frame 87. With the apparatus in this condition, when a message is being received by the receiving apparatus 36 from a remote station, the local transmitter 118 is inoperative and slide 92 remains locked in its rightward position, so that as the lifting bail 42 operates under the control of the cams located on cam shafts 66 and 67, as indicated above and as described in detail in the patent aforementioned, it will elevate both the type wheel shifting frame 46 and the ribbon shifting frame 87 until the stop projections of these frames come into abutting relation with the stepped apertures in the members 54 and 102, respectively. Stop projection 56 on the type wheel shifting frame 46 will engage the shoulder portion 64 of stepped aperture 55 or proceed to the upper portion of that aperture in accordance with whether the apparatus is conditioned for printing in the upper or lower case position. The stop projection 91, however, carried by the ribbon shift frame 87 is in alignment with the shoulder portion 106 of the step of aperture 105 and accordingly, will engage therewith whether the type wheel frame member 46 travels to the shift or unshift position. In other words, irrespective of the elevation of the type wheel, during the condition of the apparatus now under consideration, the received message will always be recorded from the upper half of the inking ribbon because the stop projection will always abut against the shoulder portion of the step of aperture 105, limiting the elevation of ribbon shift frame 87 and positioning the upper portion of the inking ribbon in the path of the type elements.

When transmitter 118 is operative and the printing apparatus is employed for producing a home record of messages transmitted by the local transmitting equipment, the transmitting cam shaft rotates once for each signal combination transmitted and during the operation of the transmitting cam shaft, cam 113 operates the follower 112 to rock locking pawl 108 clockwise about pivot 111, releasing its locking engagement with shoulder 107. Spring 98 is thereby rendered effective to draw the slide 92 leftwardly, as viewed in Fig. 1, and through the connection between slides 92 and 102, the latter slide member and, of course, the stop aperture 105 will likewise be positioned leftwardly. Shifting slide member 102 to the left removes the shoulder portion of stop aperture 105 from alignment with the stop projection 91 on the ribbon shift frame and under this condition, as the lifting bail 42 operates under the control of the cam shafts 66 and 67, it will elevate the ribbon shift frame 87 to its uppermost limit; that is, until stop projection 91 abuts against the upper portion 110 of aperture 105 which positions the lower transverse portion of the inking ribbon in alignment with the type element. The inking ribbon illustrated at 120 comprises two color bands, the upper of which may be assumed to be blue and the lower assumed to be red. With such a ribbon, the received messages are printed in blue, that is, from the upper transverse half of the ribbon, and the transmitted messages are recorded in red from the lower half of the inking ribbon. During the operation of bail 42, the pins 49 and 51 serve to guide accurately frame members 46 and 87.

As described in detail in the above-identified patent, when the printing apparatus herein dis-

closed is operating as a home recorder, in response to the depression of a key lever in the keyboard, the transmitting cam shaft, shaft 66, and shaft 67 are released in the recited order to afford overlap in the printer. The release of these shafts is such that when the shaft in transmitter 118 has completed about two-thirds of a revolution, shaft 66 is released and for approximately one-third of a revolution these shafts rotate concurrently. In order to assure the proper operation of the ribbon shift mechanism, cam 114 is oriented on shaft 66 with its lobe engaging follower 115 within the first few degrees of rotation of shaft 66, and cam 113 is oriented on the cam shaft of transmitter 118 so that its lobe will engage follower 112 within the last few degrees of a cycle of revolution; that is, during the interval in which the transmitter cam shaft and shaft 66 rotate concurrently and after cam 114 has operated to latch slide 92 in its rightward position, as viewed in Fig. 3. With the cams oriented in this manner, in each cycle of the printing apparatus cam 114 will operate its follower 115 to rock lever 117 counterclockwise and through its engagement with projection 119 position slide 92 to its rightward position if it should not already be so positioned. Spring 109 is then effective to rock latching pawl 108 counterclockwise to engage locking shoulder 107 and retain slide 92 in its rightward position. If the incoming signal combination originated at the local transmitter, cam 113 will operate after cam 114 and release pawl 108, permitting slide 92 to shift to its leftward position and condition the apparatus to record the transmitted character in its proper color.

Having provided a yieldable connection between the principal slide 92 and the auxiliary slide 102, it is not necessary to maintain a close timing relation between the restoring operation of the slide 92 and the return of the frame member 87. That is, if, assuming that the apparatus is printing a record of messages transmitted from the local transmitter, cam 114 should operate lever 117 to restore the slide 92 to normal, while stop projection 91 is still in the upper portion of the aperture 105 abutting against horizontal portion 110, the stop projection would also be in abutting relation with the vertical face of the step in aperture 105 and, accordingly, would prevent slide 102 from following the return of slide 92. Since provision has been made for a relative sliding movement between members 92 and 102, cam 114 would return slide 92 to normal and lock it in that condition and spring 104 would be distended so that when the bail 42 finally had progressed sufficiently on its return movement, to retract the stop projection 91 from engagement with the vertical portion of the step, spring 104 would be effective to cause slide 102 to follow the position of slide 92 and accordingly, return the entire ribbon shifting mechanism to normal.

The apparatus disclosed in Figs. 4, 5, and 6 is identical with that of Figs. 1, 2, and 3, with the exception of the operating mechanism for the slide members of the ribbon shift mechanism, and accordingly, the parts common to the two groups of figures bear corresponding numerals. A plate 121 which supports spools 81 for the ribbon 120 is secured to the frame of the apparatus. An elongated stud 122 is substituted for the stud 96 of Fig. 2 and a ratchet 123 and a multi-lobed cam 124 have been added, mounted on stud 122. The ratchet and cam are integrally connected for rotation on stud 122. Also, rotatably mounted

on stud 122 is an L-shaped crank 126 normally urged in a clockwise direction by a spring 127 connected to a spring post (not shown). A feeding pawl 128 is pivoted on crank 126 and is normally urged in a counterclockwise direction by a spring 129 anchored to a projection 130 on crank 126. A holding lever 131 is pivoted on stud 47 and carries a jockey roll at its leftward extremity which is normally sprung urged into engagement with ratchet 123 by a spring 132. Slide member 92 is provided with a cam projection 133 maintained in contact with cam 124 by the spring 98 of the slide member 92.

In employing the ribbon shift mechanism disclosed in Figs. 4 through 6, a solid color ribbon 120 is to be employed and the mechanism will operate as follows to assure equalized wear throughout the ribbon length: A received code signal combination, whether received from the line or from the transmitter associated with the particular printing apparatus, causes cam shafts 66 and 67 to rotate for one revolution. With each rotation of cam shaft 67, a cam 134 carried thereon is rotated and operates a bell crank follower 136 pivoted to the printer frame at 137. The end of the bell crank not engaged by the cam is in the path of the spring-urged crank 126 and as the bell crank 136 is rocked about its pivot in a counterclockwise direction by cam 134, it rocks crank 126 in a counterclockwise direction about stud 122, and feed pawl 128, which by virtue of spring 129 is in engagement with a tooth of ratchet 123, steps the ratchet counterclockwise about the stud 122. The jockey 131 is then positioned into the next recess on the ratchet and serves to hold the ratchet as positioned while spring 121 returns crank 126 to its normal position for a subsequent stepping operation.

There are provided twice as many teeth in the ratchet as lobes on the multi-lobed cam 124, and accordingly, it requires two operations of the stepping pawl 128 to travel from one lobe to the next succeeding one. When the ribbon shifting mechanism is conditioned as illustrated in Fig. 4 with the cam projection 133 engaging a lobe of multi-lobed cam 124, slide member 92 and auxiliary slide 102 are conditioned in their rightward position, aligning the shoulder portion 106 of the step of aperture 105 with the stop projection 91 so that as the bail 42 operates under the control of cam shafts 66 and 67, ribbon shift frame 87 is elevated to its lower position inasmuch as its movement is arrested by the abutment of stop projection 91 against the shoulder portion 106 of the step. The upper portion of the ribbon, accordingly, is presented to the printing point for the printing operation and at the completion of that particular cycle, cam 134 will rock bell crank 136 and step ratchet 123 in the manner above described and present a nadir to cam projection 133. Spring 98 will then be effective to draw the slide 92 to the left and through the following arrangement of slides 92 and 102, the auxiliary slide 102 will likewise be positioned to its leftward position.

In this condition, the stop projection 91 will not be in alignment with the shoulder portion of the step of aperture 105 and will be permitted on the next elevation of the ribbon frame 87 under the influence of bail 42 to raise to the upper limit 110 of the stop aperture 105 and thus present the lower half of ribbon 120 to the printing point. Toward the completion of that cycle, cam 134 again will step ratchet 123 to present a lobe of cam 124 to cam projection 133 and position the

ribbon shift mechanism again to the right to present the upper half of the ribbon to the printing point on the succeeding printing cycle. Accordingly, through the operation of cam 134, stepping ratchet 123, cam 124, and cam projection 133, the ribbon shift mechanism is positioned in alternation in its rightward and leftward position, causing printing from the upper and lower transverse halves of the ribbon, successively. Since the ribbon shift frame 87 travels to present the various portions of the ribbon to the printing point, it is immaterial that printing be from the upper or lower case; that is, from the upper or lower level of type elements on type wheel 25 and, accordingly, there will be a uniform wear on the ribbon since the ribbon will be presented in alternation for printing from the upper and lower transverse portions thereof.

There is disclosed in Figs. 7 and 8 manually operated mechanism applied to the apparatus disclosed in Figs. 1, 2, and 3, for controlling ribbon wear. Like apparatus parts bear the same reference numerals and the apparatus description will not be repeated for the mechanism common to both groups of figures. The principal slide member 92, as shown in Fig. 7, is of a modified form in that the depending portion embodying the toe projection 119 and locking shoulder 107 of Fig. 3 has been omitted and a projection 141 has been formed at the end of the slotted portion 93. An additional cam 140 provided with a projection 142 to facilitate the manual operation of the cam is rotatably supported on stud 96 for cooperation with projection 141. With cam 140 in the position shown in Fig. 7, the ribbon shift mechanism is held, through the engagement of cam projection 141 and cam 140, in its rightward position wherein the shoulder portion 106 of the step in aperture 105 is in alignment with the stop projection 91 carried on the ribbon shift frame 87 to limit the elevation of the ribbon shift frame to its lower position. With cam 140 rotated 180° from the position illustrated in Fig. 7, spring 98 is effective to draw the principal slide 92 to its leftward position and through the following connection afforded by spring 104 and stud 99, the auxiliary slide member 102 is likewise positioned in its leftward position in which condition the stop projection 91 is not in alignment with the shoulder portion of the step in aperture 105 but is permitted to travel the entire length of the aperture 105 to abutment with horizontal portion 110 before being arrested thereby.

With this particular embodiment of the invention, the cam 140 and projection 141 are conditioned to position the slide members 92 and 102 in either their rightward or leftward position, as desired, and are maintained in that condition to thereby effect printing from the same transverse half of the inking ribbon for approximately the entire ribbon length. Thereafter, cam 140 is rotated manually 180° shifting the slide members 92 and 102 to their alternate position to present the alternate transverse half of the ribbon to the printing point for the following printing operations, wherein the printing is effected for approximately the entire ribbon length from the alternate half of the inking ribbon.

Although specific embodiments of the features of this invention have been disclosed and described in detail, it is to be understood that the invention is not limited to those specific disclosures but is capable of modifications and re-

arrangements, and consequently, the scope of the invention is to be determined not by the specific disclosures but in accordance with the appended claims.

What is claimed is:

1. In a printing telegraph apparatus the combination of a platen, a shiftable type wheel, a shiftable ribbon carrying mechanism, cyclically operable means to shift said type wheel and said ribbon carrying mechanism into alignment with said platen for printing, means for varying the degree of shifting of said type wheel by said shifting means, and separate means for varying the degree of shifting of said ribbon carrying mechanism by said shifting means whereby the character of the printing is varied.

2. A printing telegraph apparatus comprising means to transmit code signal combinations, means to receive code signal combinations, means to record characters corresponding to code signal combinations received or transmitted, said recording means including a platen, a type wheel, a ribbon carrier, a multi-color band ribbon on said carrier, cyclically operable means to elevate said type wheel to alignment with said platen, cyclically operable means to elevate said ribbon carrier to present a given color band to said type wheel and said platen for recording characters corresponding to received code signal combinations, and means controlled by said transmitter to cause said ribbon carrier to be elevated to a different height to present a different color band to said type wheel and said platen for recording characters corresponding to transmitted code signal combinations.

3. In a printing apparatus, a ribbon shift mechanism comprising a shiftable ribbon carrying frame including a stop projection, means to shift said frame, means for varying the shifting of said frame comprising a principal sliding member, an auxiliary sliding member supported by said principal sliding member and having a stepped aperture through which said stop projection extends, and means to selectively position said sliding members to determine the degree of shifting of said frame through the engagement of said stop projection with the aperture in said auxiliary sliding member.

4. In a printing apparatus, a ribbon shifting mechanism comprising a shiftable ribbon carrying frame, means to elevate said frame to present the ribbon to the printing point, means for limiting the elevation of said frame including a slideable stop member provided with a stepped stop aperture engaged by said frame, means for normally retaining the step of said aperture in a position to allow a predetermined elevation of said frame, means to shift said slideable stop member to allow a different predetermined elevation of said frame, and means to restore said slideable member from its shifted to its normal position at the beginning of each printing cycle.

5. A ribbon shift mechanism for printing apparatus to align the upper portion of an inking ribbon and the lower portion of the ribbon at the printing point alternately, comprising a ribbon shift frame, a stop projection on said frame, means to elevate said frame, a slideable stop member having a stepped aperture into which said stop projection extends to limit the elevation of said frame, a cam following projection on said slideable stop member, a multi-lobe cam, means for urging said cam following projection into contact with said cam, means to step said cam in each printing cycle to slide said slideable stop

member and position the step alternately into and out of the path of said stop projection.

6. In a printing apparatus, a type carrier having a plurality of rows of characters, means to shift the type carrier effective in each recording cycle to bring one row of characters into printing position, means to vary the rows of characters selected in accordance with the character to be printed, an inking ribbon, means to shift said ribbon from a retracted position to the printing position in each cycle, means to maintain the shift of said inking ribbon to a predetermined degree irrespective of the shift of said type carrier, and means to determine the shift of said ribbon for different operating conditions.

7. In a printing apparatus, a ribbon shift mechanism comprising a shiftable ribbon carrying frame, means to shift said frame, means for varying the shifting of said frame including a principal sliding member, an auxiliary sliding member carried by said principal sliding member, a plurality of stopping devices carried by said auxiliary sliding member for engagement with said frame to determine the degree of ribbon shift, and means to selectively position said sliding members whereby a predetermined one of said stopping devices is rendered effective to arrest the travel of said frame and determine the degree of ribbon shift.

8. In a printing apparatus, a ribbon shift mechanism comprising a ribbon carrying frame, means to shift said frame to present the ribbon to the printing point, means for limiting the degree of shifting of said frame including a slideable stop member having a plurality of stopping devices for engagement with said frame, means for normally retaining one of said stopping devices in operative relation with respect to said frame to allow a predetermined degree of ribbon shift, means to condition said slideable stop member to position another of said stopping devices in operative relation with respect to said frame to allow a different degree of ribbon shift, and means to restore said slideable stop member to its normal position in each cycle of the printing apparatus.

9. In a printing telegraph apparatus, a printer for recording local and remote signals including a platen, a movable type member, an inking ribbon having a plurality of color areas, a movable ribbon carrier, cyclically operable means to elevate said type member to the printing position, cyclically operable means to elevate said ribbon carrier to interpose said inking ribbon between said type member and said platen for printing, means under the control of local signals for enabling said ribbon carrier to be elevated to a predetermined position to present a predetermined color area to the printing point, and means under the control of remote signals for causing said ribbon carrier to be elevated to a different predetermined position to present a different color area to the printing point.

10. In a printing apparatus, a cyclically operable ribbon shift mechanism including a ribbon carrier movable to different predetermined positions, a stop engaging means carried thereby, a reciprocating slide having a plurality of stops for cooperating with said stop engaging means to determine the elevational position of said carrier, and means for shifting said slide at the end of each printing cycle to alternately present one or the other of said stops to said stop engaging means to thereby enable said carrier to be alternately raised to a different predetermined

position for each successive printing operation.

11. In a printing apparatus, a cyclically operable ribbon shift mechanism including a ribbon carrier movable to different predetermined positions, a stop engaging means carried thereby, a reciprocating slide having a plurality of stepped apertured stops for cooperating with said stop engaging means to determine the elevational

positionment of said carrier, and means for shifting said slide at the end of each printing cycle to alternately present one or the other of said stops to said stop engaging means to thereby enable said carrier to be alternately raised to a different predetermined position for each successive printing operation.
